CARTON FORMING AND FILLING MACHINE

Eugene S. Tascher, Ingleside, Ill., and William Bazant, Wyandanch, N. Y., assignors to National Biscuit Company, New York, N. Y., a corporation of New Jersey

Application April 17, 1941, Serial No. 388,958

4 Claims. (Cl. 93—3)

1

Our invention pertains to carton forming and filling machines.

The embodiment of our invention that we have selected for illustration is designed particularly for forming and filling lined cartons, such as are commonly used for packaging crackers, cookies, and other food products but the invention is not limited thereto. Such lined cartons are formed by folding together and interlocking the liner and carton blank, the carton blank having side and end flaps and interlocking tongues and slits that are folded and interlocked while the carton blank and liner are being folded together.

An important object of our invention is to provide a packaging machine, or a carton forming and filling machine, wherein the articles being packaged automatically control the feed and timing of the machine.

Another object of the invention is to provide means in a packaging machine that will measure by volume and with exactness the weight or unit quantity of the articles that will be contained in the package.

Another object is to provide a feeding and control means whereby an exact predetermined volume (and hence weight) of the articles will be delivered to the packaging machine each time, the means being arranged so that it cannot operate until that exact volume is ready to be delivered.

Another object is to provide means for adjusting the volume measuring means so that the exact required volume will be measured and delivered each time.

Another object of the invention is to provide means in a carton forming and filling machine whereby it may operate only as a carton forming machine to form cartons, or cartons and liners from appropriate blanks, that may be removed from the machine after being formed to be filled and closed elsewhere.

Still another object is to provide means, whereby the machine may be adapted to forming, locking and filling cartons of many different sizes and shapes.

Yet another object is to provide means for delivering a fixed volume of the merchandise to be packaged to a hollow former having an open bottom but in which the merchandise will be held by clamping means until the former has been brought into or substantially into contact with the carton blank or carton liner.

The above and other objects and advantages over prior carton forming and filling machines are attained by our invention, one form of which we have illustrated in the accompanying draw-

2

ings to which reference is had for a full understanding thereof.

Fig. 1 is a top plan view of an automatic carton forming and filling machine embodying our invention, this form of the invention embodying matter that was first disclosed and claimed in our co-pending application, Ser. No. 330,140.

Fig. 2 is a front elevation, partly in section on the line 2—2 of Fig. 1.

Fig. 3 is a side elevation, partly in section on line 3—3 of Figs. 1 and 2.

Fig. 4 is a vertical section taken substantially on line 4—4 of Figs. 1 and 2.

Fig. 5 is a top plan, partly in section on line 5—5 of Fig. 2.

Fig. 6 is a view, partly broken away and partly in section, on line 6—6 of Fig. 2, showing the article feeding and measuring mechanism.

Fig. 7 shows a leader or starting block that is used at the head of a column or stack of articles as they are being advanced to the machine.

Fig. 8 is a section on line 8—8 of Fig. 6.

Fig. 9 is a section on line 9—9 of Fig. 2.

Fig. 10 is a section on line 10—10 of Fig. 9.

Fig. 11 is an enlarged detail view taken substantially on line 11—11 of Figs. 6 and 9.

Fig. 12 is a section taken substantially on line 12—12 of Fig. 2.

Fig. 13 is a side view, taken on line 13—13 of Figs. 2 and 12, showing the cam and sliding link for operating the carton feed carriage.

Figs. 14 to 18 show five stages in the formation of a carton from a blank and liner.

Our invention in its many aspects and details is adapted to use with different kinds or types of carton forming machines.

In Figs. 1 to 13, we have shown our invention embodied in an automatic carton forming and filling machine, this embodiment including matter that is also shown in our co-pending application, Ser. No. 330,140, now Patent No. 2,315,670.

The machine illustrated is adapted particularly for packaging crackers or other forms of biscuit that are delivered to the machine stacked on edge, the machine automatically measuring off definite quantities of crackers or other articles from the stack and forming a carton about each measured quantity.

Referring to Fig. 12, an endless belt 123 delivers the crackers to a transfer plate 124 in front of a plunger 125 that is in alignment with a follower 126. The follower 126 is connected to a rack 127 which engages a pinion 128 that is secured to a grooved pulley 129 over which a cord passes that is attached at one end to a

weight adapted to rise and fall in the well 130. A mercury switch 131 (which may be double switch or two switches secured together) is adapted to be tilted and closed by a striker 132 on the rack 127 when the follower 126 is at the extreme left end of its movement. One side of the switch 131 is in the circuit of a solenoid 133 (Figs. 1 and 2) which through a system of levers and cams (as shown in Fig. 2) operates to lift the rails 123' on the two sides of the conveyor 123 when the solenoid 133 is energized to bring the crackers on the conveyor to rest.

The operation of pusher 125 to feed measured quantities of the crackers from the forward end of the column on the conveyor 123 to the packaging machine is controlled through a solenoid 134 (Fig. 3) that in turn controls the operation of a one-revolution clutch. The solenoid 134 is in a circuit that is controlled by the switch 131 which is a double switch or two independent switches, one in the circuit of the solenoid 133 and the other in the circuit of the solenoid 134. Therefore, each time that the follower 126 is pushed to the left (Fig. 1), the circuits through both of the solenoids 133, 134 will be closed which will cause the plunger 125 to feed a definite volume and therefore a definite weight of the crackers from the head of the column into the packaging machine where the carton will be formed around them.

Reference will now be had to Figs. 1 to 4 for a general description of the cracker measuring and delivery mechanism and carton forming device.

An electric motor 135, preferably having a built in adjustable speed reduction drive, through a chain 136 drives a cam shaft 137 that is journaled in bearings in the lower part of the frame 138 and extends across the frame. At its opposite end, the shaft 137 has a sprocket 139 (Figs. 2 and 9) which through a chain 140 drives a cam shaft 141, journaled in the upper part of the frame 138 parallel to the lower cam shaft 137 (Figs. 2 and 4). The shaft 137 has keyed to it a gear 142 meshing with a gear 143 that is keyed to a third cam shaft 144 journaled in the lower part of frame 138 parallel to the shaft 137.

The motor 135 does not drive the shaft 137 continuously, but intermittently through the one-revolution clutch that is controlled by the solenoid 134, previously referred to. (Figs. 1, 2 and 3). The chain 136 drives a sprocket 145 that is fixed to one element 146 of the one-revolution clutch rotatable on the shaft 137. The other element 147 of this clutch is keyed to the shaft 137 and normally engages the stop 148 which holds it against rotation. The stop 148 is pivoted at 149 and a spring 150 urges it into the path of the clutch element 147. (Fig. 3). The free end of the stop 148 is connected to the core 151 of the solenoid 134. When the solenoid 134 is energized, it pulls down on the stop 148, tilting it about the pivot 149 to release the clutch which then drives the shaft 137 one revolution and the packaging machine through one cycle of movements.

Adjacent the gear 142, the shaft 137 has a cam 152 keyed to it (Figs. 1, 2 and 3) having a groove 153 in which the roller 154 rides. The roller 154 is secured to a sliding link 155 which is forked at its lower end to slidably engage over the shaft 137 and at its upper end is pivotally connected to an arm 156 keyed to a rock shaft 157 journaled in the upper part of the frame 138. Another arm 158 is keyed at one end to the rock

shaft 157 and at its other end is connected to the upper end of a yoke-like link 159, which flares outwardly at its lower end to provide spaced bearings 160, 161 (Figs. 2 and 5) for a shaft 162, each end of which carries a pinion 163, 164 engaging the vertical racks 165, 166 fixed to the frame. The ends of shaft 162 extend beyond the pinions 163, 164 and are journaled in sliding blocks 167, 168 that slide in vertical guide ways 169, 170 on the frame adjacent the racks 165, 166 (Fig. 5).

A hollow rectangular former 171, within which the measured volume of crackers is held while the carton blank and liner are folded about it, is connected to a U-shaped cross-bar 172 (Figs. 2 and 5) that slides vertically in guides 173, 174 in the frame. Secured to each side of the cross-bar 172 is a rack 175, 176 which engage the gears 163, 164 respectively, opposite the fixed racks 165, 166. A pair of chains 177, 178 are connected to the top of the cross-bar 172 and extend over idler sprockets 179, 180 at the top of the frame and over a second pair of idlers 181, 182 that are above the wells 183, 184. Counter weights 185, 186 attached to the lower ends of the chains 177, 178 are adapted to rise and fall in the wells and counterbalance the former frame 172 and its associated parts.

When the cam 152 makes one revolution upon release of the clutch member 147, the sliding link 155 rises and falls and rocks the shaft 157 together with the arm 158. This causes the shaft 162, through its connection to the link 159 to ride up and down in the guide ways 169, 170. The pinions 163, 164 on shaft 162 run on the fixed racks 165, 166, and by reason of their engagement with the movable racks 175, 176 will cause the latter, and hence the former 171, cross-bar 172 and their connected parts to make vertical strokes of twice the length of the stroke of the link 159 and shaft 162.

Referring again to Figs. 1 to 5, the cam shaft 141 has a cam 187, a sprocket 188 and a cam 189 keyed thereto. The cam 187 has a race in which the roller 190 on sliding link 191 runs. The link 191 is forked at its end adjacent the cam and slidably engages the shaft 141. The opposite end of link 191 is pivotally connected to a swinging arm 192 intermediate its ends, the upper end of the arm being pivotally supported on a bracket 193 secured to the frame of the machine. The lower end of arm 192 is connected by a short link 194 to the plunger 125 that feeds the crackers to the hollow former or mandrel 171. It will be noted on reference to Fig. 4, that the race in the cam 187 is concentric with the shaft 141 through about 240° and that the active portion of the race embraces only 120° or less, so that the action of the plunger 125 takes place during one third, or less than one third, of the time for a complete cycle of movement of the package feeding and forming.

The sprocket 188 drives a chain 195 that drives a second sprocket 196 keyed to a shaft 197 journaled on the frame of the machine (Figs. 2 to 4). This shaft 197 carries a cam 198, the rise of which engages a roller 199 on a lever 200, pivoted at 201, and presses it to the right (Fig. 2) against the tension of a spring 202 that is secured to a depending guide finger 203 that is a part of the lever 200. As is best shown in Fig. 4, the hollow former or mandrel 171, is open on both the bottom and on the side toward the plunger 125. The plunger 125 has a forwardly extending plate 204 which is in alignment with the belt 123 when the plunger is withdrawn and receives the

crackers from the head of the stack. This plate 204 supports the crackers as they are pushed by the plunger 125 into the former 171, but when the plunger and plate are withdrawn, the crackers would drop out through the open bottom of the former except for the provision of means to hold them until the former is lowered into contact with the carton blank. This holding means is actuated from the cam 198 and lever 200, as best shown in Figs. 13, 15 and 16. A lever 205 is pivotally secured intermediate its ends to the cross-bar 172 that supports the former 171. At its upper end, this lever has a grooved roller 206 that rides along the edge of the finger 203, and at its lower end has a fork 207 that fits over a pin secured to a slide 208 that slides on a guide bar 209 secured in the former 171 above the top edges of the crackers that are to be packed. As best shown in Fig. 4, the slide 208 carries a bracket 210 that is secured to a thin sheet metal holding plate 211, which is relatively broad and (as shown in Figs. 6 and 8) lies snugly against one side of the former 171 when a measure of crackers is being pushed in and extends below their top edges. Figs. 6 and 8 show a measure of crackers 293 being pushed into the former 171 by the plunger 125. When the plunger 125 is at the inner end of its delivery stroke and the measure of crackers 293 sufficient to fill a carton is fully within the former 171 but supported by the plate 204, the cam 198 will release the roller 199 of the lever 200 and the guide finger 203 will be pulled to the left (Fig. 2) by the spring 202. This will rock the roller 206 at the upper end of lever 205 to the left and move the forked end 207 to the right together with the holding plate 211. The holding plate presses against one side of the measure of crackers and forces them against the opposite side of the hollow former 171 with a gentle, yet sufficient, force to hold them in the former while the support 204 is withdrawn and the former then lowered into contact with the carton blank and liner through operation of the cam 153 and its connected linkage. When the crackers and former 171 are forced down during the operation of folding the carton blank and liner, the roller 206 rides down along the finger 203 and keeps the holding plate 211 pressed gently against the crackers. By the time the carton is formed, the rise on the cam 198 presses the lever 200 to the right (Fig. 2) so that the holding plate 211 releases the crackers and the former 171 is then withdrawn from the carton leaving it filled with the crackers ready for closing.

Referring now to Figs. 3 and 5, the cam 189 on the shaft 141 engages and is adapted to actuate a roller 212 mounted on an arm 213 that is secured to a rock shaft 214 mounted in bearings near the top of the frame 133. Adjacent its two ends, the shaft has a pair of arms 215, 216, keyed to it, the free ends of the arms being pivotally connected to the upper ends of two connecting rods 217, 218 the lower ends of which are connected to two liner fold straightening fingers 219, 220, which are pivoted at one end to the frame and extend inwardly from the two sides in position to engage within the rear folds of the liner to hold them out smooth and aid in forming the crease so that they can be folded down without wrinkling or tearing when the last folds are made in the blank and liner as shown in Fig. 15.

Between the arms 215, 216, the rock shaft 214 carries a third arm 221 that is connected to the upper end of a connecting rod 222 (Figs. 4 and 5),

the lower end of which is connected to a short arm 223, fixed to a rock shaft 224, mounted in bearings on the rear removable top plate 225, which forms part of a removable unit. The shaft 224 has three liner holding bars 226, 227, 228 secured to it that are adapted to be tilted down and overlie but not rest on the liner to hold it smooth during the initial part of the folding operation (Figs. 4, 5, 9 and 15). One form of carton blank 229 and liner 230 are indicated in Figs. 4, 9, 14 to 18.

Referring to Fig. 3, the cam 189 is concentric through about 300° so that the holding bars 226, 227 and 228 are in their lowered position and the fold straightening fingers 219, 220 in raised or inactive position during that interval. The operation is such that as the bars 226, 227, 228 are raised the fingers 219, 220 are lowered.

The bars 226, 227, 228, overlie the liner 230 until it and the carton blank are folded to about the extent shown in Fig. 15. Now it is time to turn up the back side of the carton and liner, so the bars are raised and the fingers 219, 220 tilted down to engage within and straighten out the folds 231 (Fig. 16) that are formed in the liner when the rear side is folded up. These fingers are tilted back or raised very quickly by the cam 189 to permit the end flaps of the carton to be folded in as shown in Fig. 17. At the same time the bars 226, 227, 228 are again lowered, ready to hold down the next carton and liner that are inserted.

Turning now to Figs. 2, 3, 4 and 9, a removable front unit is secured to the frame 133 by a top plate 232, cross plate 233, and brackets 234, 234', the latter having guideways 235, 235' for the sliding blocks 236, 237 which form bearings for the opposite ends of a shaft 238. A pair of pinions 239, 240 keyed to this shaft mesh with racks 241, 242 fixed to the brackets 234, 234' and with movable racks 243, 244 fixed to the sliding feed carriage 245. Guide bars 246, 247 (Fig. 2) secured to the brackets 234, 234' provide runways for the racks 243, 244 and guides for the carton blanks and liners as they are fed in. A link 248 is connected at one end to shaft 238 and at its other end to an arm 249 keyed to a rock shaft 250 mounted in bearings 251, 252, in the lower frame. A short arm 253, keyed to shaft 250 adjacent the bearing 252, is connected to a sliding link 254 that has a forked inner end slidably engaging shaft 144 and a roller running in the groove of a cam 255 keyed to a shaft 144 (Figs. 9 and 13). The arm 249 may be adjustably connected to shaft 250.

The shaft 144 has a second cam 256 keyed to it adjacent the cam 255 and gear 143 (Fig. 2). This cam 256 has a groove 257 (Fig. 3) in which a roller runs that is secured to a sliding link 258, the upper end of which is pivoted to a short arm 259 fixed to a rock shaft 260 mounted in bearings 261, 262, 263 (Fig. 9) so as to lie adjacent the inner ends of the guides 246, 247.

The top plate 232 is L-shape in cross section and the inner ends of the guide bars 246, 247 are secured to it. (Figs. 4, 9 and 10.) A carton folding plate 265 usually made from relatively thin metal, is fixed to the shaft 260, and normally rests in a shallow recess in plate 232. A pair of side wings 266, 267, are pivotally connected to the two sides of plate 265 and normally lie in the same plane. The plate 265 is adapted to turn up the front panel of the carton, and the wings 266, 267, to turn in two of the carton end flaps, as shown in Fig. 15.

A pair of toggle levers 268, 269 are pivoted intermediate their ends to the under face of the plate 265 (Fig. 10). The outer ends of these levers are connected by short links 270, 271 to the lower faces of the wings 266, 267. A bell crank lever 272, also is secured to the under side of the plate 265, its horizontal leg having a slot near its free end engaging the adjacent ends of the levers 268, 269 (Figs. 4 and 10). The vertical leg of the lever 272 is connected to one end of a spring 273, the other end of which is connected to an adjustable fastener 274 secured to the removable cross-plate 233. When the shaft 269 is rocked to raise the plate 265 to fold up the front wall of the carton (as shown in Fig. 15), the wing carries the lever 272 up with it and tends to tilt the horizontal leg 272 toward the vertical, but this tilting movement is resisted by the pull of the spring 273. The result is a rocking of the lever 272 relative to the plate 265 which pulls the inner ends of the 20 toggle levers 268, 269 away from the plate 265, thereby folding the wings 266, 267, inward, as shown in Fig. 15.

As best shown in Figs. 4 and 9, there is an opening between the rear top plate 225 and shaft 260, 25 through which the former 171 moves up and down. The former 171, rises above this opening to the position shown in Fig. 4 to receive a measured volume of crackers, and passes down through the opening during the operations of folding the carton blank and liner about it and depositing the crackers in the carton as it is withdrawn.

A pair of front flap guides 275, 276 (Figs. 9, 10, 12) are secured to vertical front guides 264, 264' and extend toward rear top plate 225. The guides 275, 276 are spaced apart a distance slightly greater than the length of the former 171 so that the plates will press against the end flaps of the carton as the blank and liner are 40 carried down between these plates by the former. The front guides 264, 264' are secured to the top plate 232 and cross plate 233 and are removable therewith.

A pair of folding wings 277, 278 are hinged at 279 and 280 to a pair of brackets 281, 282 that are secured at 283, 284 to the rear plate 225, Fig. 9. Each of these wings has a lip 285, 286 that projects into the path of the former 171 as the latter travels down past the plate 225.

The function of these two wings 277, 278 is to fold up the bottom flap of the carton and the overlying part of the liner just as the rollers 46, 47 function in Fig. 16.

The rear plate 225 has two downwardly extending guides 287, 288 the forward edges of which curve inwardly as shown at 289, 290 (Figs. 2, 4, 10) so as to engage and fold inwardly the folds 234 in the carton liner and the end flaps 321, 322 of the carton lying under the liner to the position shown in Fig. 17. The vertical parts of these guides 287, 288 below the curved portions are spaced apart a sufficient distance to just clear the former 171 and carton blank and liner as they are forced down during the folding operations. The space between these two vertical portions is substantially the same as the distance between the guides 275, 276.

Referring to Figs. 4 and 12, adjacent the lower ends of the guides 287, 288 there are adjustably mounted back closing plates 291, 292 which engage the back side of the carton blank as it is pushed down by the former 171 and turn it forward so that the locking tongues on the end flaps enter the slits in the carton and lock it in formed

75

position. A pair of guides 293, 294 are secured to the upper surface of the top plate 225 and serve to guide the carton blank and liner as they are inserted, Fig. 19.

As best shown in Figs. 4, 9 and 12, the liner holding fingers 226, 227, 228, the guides 293, 294, the arms 281, 282, the vertical guides 287, 288 and the back closing plates 291, 292 are all secured to and carried by the rear top plate 25 and are removable with it as a unit.

Referring to Figs. 10 and 12, each of the guides 275, 276 carries a yieldably mounted breaker finger 295, 296 each of which projects through an opening in the guide that is in alignment with the slit formed in the carton and opens the slit in the carton as it passes by during the formation of the carton.

Each of the front guides 264, 264' has a bearing 297, 298 in which a shaft 299 is fixed. Near each end, the shaft carries a tongue guide finger 300, 301 which is located so that the fork or groove in each guide engages a locking tongue on the carton blank and guides it in toward the slit in the carton blank with which it interlocks.

Below the guide fingers, each of the front guides carries a yieldably mounted roller 302, 303 which, as the carton blank descends, open the slits in the opposite end flaps for the reception of the locking tongues. The carton former or mandrel has an opening 304 cut in each side (Fig. 4) which openings coincide with the slits in the carton blank as it is being formed and these openings travel down in alignment with the breaker fingers 295, 296 and the rollers 302, 303. The slits in the carton coincide with the lower edges of the openings 304 so that only that portion of the carton above the slit can be pressed inward to open it.

The front plate 232, the lower cross-plate 233 and brackets 234, 234' are connected together and are removable as a unit carrying with them the guides 264, 264', the guides 275, 276, the guide fingers 297, 298, the rollers 302, 303, the front plate 265, and the flaps 266, 267, together with their operating levers.

Instead of the movable flaps 227, 228 shown in Figs. 9 and 11, we may use a roller 47 on each of the arms 281, 282 as shown in Fig. 14.

The method of folding the carton blank and liner is shown in Figs. 14 to 18. A carton blank 229 and liner 230 are fed into the machine as shown in Fig. 4 spanning the gap between the front plate 232 and the rear plate 225. The carton blank is marked with score lines so as to provide a panel 310 which will form the bottom of the carton and which lies directly over the opening in the top frame and beneath the former 171. Other score lines on the blank provide bottom end flaps 311, 312, a front panel or side 313, a back side or panel 314, a cover 315 and a tuck 316. At the two ends of the front panel 313 are front flaps 317, 318 each of which is provided with a slit 319, 320. The back wall of the carton 314 is provided with opposite end flaps 321, 322 each of which has a locking tongue 323, 324 which, when the carton is formed enter the respective slits 319, 320. Cuts 325, 326 separate top closing flaps 327, 328 from the cover 315 and these top flaps are connected along score lines to the end or locking flaps 321, 322. This carton blank is of usual form.

When the carton blank and liner have been inserted in the machine as shown in Figs. 4 and 14, the former 171 holding a measured quantity of crackers 293 descends. The first operation as

the bottom of the former starts to force the carton blank down between the front and rear top plates is for the cam 256 to rock the shaft 260 which raises the front plate 265 folding up the front of the liner and the front wall 313 of the carton. At the same time, through the pull of the spring 273, the end flaps 266, 267 are turned in folding in the sides of the liner and the front end flaps 317, 318 as shown in Fig. 15. As the former continues to press the carton blank and liner down the next operation is for the wings 277, 278 (Fig. 9) or the rollers 47 (whichever is used) to fold up the bottom end flaps 311, 312 together with the overlying fold of the liner as shown in Fig. 16. In this position the fold straightening arms 219, 220 have straightened out the rear folds 231 in the liner and the carton is substantially in the position shown in Fig. 16. The fingers 219, 220 are now swung up and as the carton continues to descend, the back panel 314 of the carton and top 315 are folded up by the downwardly and inwardly inclined front edge of the rear plate 225. The inclined faces 289, 290 of the vertical guides 287, 288 engage the flaps 321, 322, 327 and 328 and gradually fold them inwardly. During this time the slits 319, 320 have passed beneath the breaker fingers 295, 296 which break open the slits provided they have not been cut fully open when the carton blanks were formed. As the carton descends further the locking tongues 323, 324 will engage in the grooves in the guide fingers 297, 298 which are inclined inwardly toward the former and as the tongues slide along them they are turned in toward the slits and also are positioned the correct distance from the slits so that when the rear side of the carton is folded into its final position by the plates 291, 292, the tongues will be in exact alignment and ready to enter the slits 319, 320 when the latter are opened by pressure of the rollers 302, 303 on both the tongues and the carton above the slits. These rollers not only open the slits but also press the locking tongues firmly against the sides of the flaps 317, 318 directly above the slits so that as the tongues are pressed forward by the back closing plates 291, 292, the tongues must enter in the slits and lock the carton in formed position. As the former 171 carries the carton down below the rollers 302, 303 it reaches the end of its stroke and the holding plate 211 is moved to release the crackers 293. The former is now withdrawn and the fully formed box filled with crackers as shown in Fig. 18 drops to the conveyor belt 329, Fig. 2, which carries it up to the closing machine.

The belt 123 (Figs. 2, 5, 6, and 8) is driven continuously but the stack of crackers (the front edge of which is indicated at 330) is advanced intermittently, the crackers coming to rest when the rails 123' raise them above the belt.

Adjacent the plunger 125 is a bracket 331 having guides 332, 333 in which the stem 334 of a cracker holder is slidably mounted. At its inner end the holder has a soft head 335, made from sponge rubber or other suitable material, and at its outer end has a finger 336 which projects into the path of the plunger 125. A light coil spring 337 bears at its inner end on a shoulder on the stem 334 and at its outer end bears against the guide 333. The spring normally urges the soft head 335 inwardly so that when released it engages the stack of crackers as shown in Fig. 6. The function of this holder is to hold the front of the stack of crackers

so that they will not fall over when the plunger 125 has pushed a measured quantity of crackers 293 into the hollow former 171. The holder holds the front of the stack of crackers from tipping over until the follower 126 returns into engagement with the front crackers of the stack. When the plunger 125 is retracted it strikes the finger 336 and withdraws the holder out of contact with the crackers as best shown in Fig. 5.

In Fig. 7, we show a metal leader or starting block 338 that is used at the head of the stack of crackers on the belt 123 when starting up the machine. This starting block may be formed from sheet metal or cast and is provided with two feet 339, 340 which will span the belt 123 and rest on the rails 123'. The block is hollow so that it will pass over, without touching, the follower 126. The block, partly broken away, is shown in Figs. 5 and 6. When the machine is started up, one of these blocks is placed at the entrant end of the conveyor 123, and is supported on the rails 123'. As the stack of crackers is advanced by the belt, the block is pushed ahead on the rails by the advancing stack and keeps the first crackers standing on edge until they reach and are held by the follower 126. The hollow starting block then passes over the follower and no longer functions. It may be removed from the machine or left standing in its inactive positions (as shown in Fig. 6) until the machine is next started, when it will again be placed in position to lead the stack of crackers.

When the follower 126 is released and returned toward the front of the stack of crackers, its motion will be very rapid caused by the drop of the weight in the well 130. If this return movement is not checked, the follower may strike the crackers with sufficient force to break them. In order to check this return movement of the follower, the bottom of the well 130 is closed so as to provide a dash-pot for the falling weight as shown in Fig. 2. However, as the weight drops, the air must escape from the well which is provided with openings 339, that may be of any size or shape adapted for the purpose, through which the air can escape until the lower edge of the falling weight passes the lower edge of these openings after which the air must escape through the narrow space between the walls of the well and the sides of the weight and will cushion the last part of the downward movement of the weight and cause the follower to contact the crackers gently. The contact pin or striker 132 is adjustable with respect to the follower 126, so that the timing of the machine may be adjusted to enable the plunger 125 always to push exactly the necessary volume of crackers from the head of the stack on the transfer plate 124 into the former 171. These pins may be adjusted in any manner as by the clamp shown holding the pin 132 in Fig. 8.

The operation of the cracker feeding and measuring mechanism is best illustrated in Figs. 1, 2, 5, 6 and 8. When the machine is started one of the starting blocks 338 is placed on the rails 123' at the righthand end of the belt 123. The crackers are fed to the belt stacked on edge and as the belt advances carrying the crackers it also carries the starting block forward until the block passes over the follower 126 and the advancing stack of crackers contacts the follower. The follower is pressed back by the advancing crackers until it reaches the position shown in Figs. 6 and 8 at which time the switch 131 is tripped by the striker

132 which closes the circuits through the solenoids 133 and 134. The solenoid 133 then operates to lift the rails 123' above the surface of the belt 123, thereby lifting the crackers out of contact with the belt so that they come to rest.

At the same time the solenoid 134 is energized which withdraws the stop 143 from the clutch element 147 so that the motor 135 starts to drive the shaft 137 through one revolution which carries the mechanism through one complete cycle, at which time the shaft 137 again comes to rest by engagement of the clutch element 147 with the stop 148.

With the stack of crackers now at rest and the shaft 137 starting its rotation, the plunger 125 starts its inward movement as shown in Fig. 6 and pushes a measured quantity of crackers 293 from the front of the stack into the hollow former 171.

When the plunger started its inward stroke, 20 it released the finger 336 of the cracker holder which permitted the soft head 335 to engage the front of the remaining stack of crackers and hold them in position as shown in Fig. 6. When the measured quantity of crackers is pushed inward 25 past the follower 126, the follower is returned by the weight dropping in the well 130, the head of the follower passing through the slot 340 (Fig. 4) in the plunger 125 until it comes in contact with the head of the stack of crackers remaining on the transfer plate 124 as shown in Fig. 5, or with the wall of the plunger that is in contact with the head of the stack of crackers when the slot 340 does not extend all the way through. The clamp 211 is now operated to grip the crackers 35 in the hollow former 171 and as the plunger 125 continues its return stroke it strikes the finger 336 and withdraws the head 335 out of contact with the stack of crackers. The return of the follower 126 withdraws the striker 132 from the switch 131 so that the circuits through the solenoid 133, 134 are opened. This drops the rails 123' so that the crackers again rest on the belt 123 and are carried forward. The former 171 is now moved downward through operation of the cam 187, a carton blank and liner having been fed into position beneath the former as previously described. As soon as the stack of crackers has again advanced so as to push the follower 126 to the left and again close the circuits through the solenoids, the mechanism operates through another cycle.

The arms carrying the tongue presser rollers 302, 303 preferably carry tongue guides 302', 303' which may be made from thin spring steel or other suitable material. These guides with some sizes of cartons and certain kinds of carton material are desirable to insure that the locking tongues enter correctly and timely under the presser rollers. As clearly shown in Fig. 2 the arms carrying the rollers 302, 303 are urged inwardly by coil springs or other suitable means. While we have shown rollers for opening the carton slits, rounded surfaces or cams on the arms operate satisfactorily but there is less friction and wear when rollers 302, 303 are used.

The fold straightening fingers 219, 220 shown in Fig. 2 generally are not necessary when the cartons are small, as say less than one pound capacity, but when larger cartons are used, they assist materially in keeping the liner folds straight and contribute to higher speed of operation.

The machine is readily convertible to use with different size cartons. As best shown in Figs. 9

and 11, the rear unit is secured to the frame by four bolts 341, 342, 343, 344 and may be positioned accurately on the frame by dowels 345, 346. All that is necessary to remove this unit and replace it with another one is to remove the four bolts and lift out the unit. It is then replaced with another unit which is drilled to receive the dowels 345, 346 and is secured in the same position by the bolts 341 to 344. The front unit is 5 secured to the top of the frame by four bolts 347, 348, 349, 350 (Fig. 9) and the cross-bars 233 is secured by four bolts 351, 352, 353, 354 (Fig. 2). When it is desired to remove this unit the arm 249 is disconnected at its upper end and the link 258 is disconnected from the arm 259. The eight 10 bolts are then removed and the front unit can be lifted off. This operation is reversed to install a unit to operate on carton blanks of a different size.

The carton former or mandrel 171 will also have to be changed but the different size mandrel will be connected to the cross-bar 172 in such position that its lower edge will occupy the same relative position as the lower edge of the former shown, and thus no change need be made in the timing of any of the mechanism.

While we have illustrated a machine in which a measured quantity of articles is fed into a hollow mandrel and the carton formed about the contents, the machine is adapted to form empty cartons and liners. Also, instead of filling the mandrel with a measured quantity of relatively large crackers or biscuit, it is contemplated that the mandrel may be filled by discharging a pre-determined weight or volume of smaller articles into the mandrel after it has been brought into contact with the carton blank and while the blank is being folded about it.

Having thus described our invention and illustrated how it may be used in carton forming and filling machines, we claim as our invention all adaptations and equivalents thereof that may come within its spirit or within the scope of any of our claims.

What we claim is:

1. In a machine of the class described, the combination of an endless conveyor, means for driving the conveyor continuously, rails adjacent the edges of the top run of the conveyor and normally below the same, means for supplying stacked articles to the receiving end of said upper run and delivering them at the other end, said articles extending beyond the conveyor and over the rails, means for raising said rails thereby to lift said articles above said conveyor, a plunger having a receiving plate in the path of the conveyor adjacent its delivery end adapted to receive articles from the conveyor, a hollow former adjacent the said receiving plate, means for moving said plunger and receiving plate to and from the former, and means actuated by forward movement of the articles on the conveyor when a definite quantity of articles have been received on said receiving plate to actuate said rail raising means whereby said articles come to rest and said plunger moving means is operated to deliver the articles on said plate to the hollow former.

2. In a machine of the class described, the combination of a continuously driven endless conveyor carrying a continuous row of articles on its upper run, a plunger having a receiving plate adapted to receive articles from the delivery end of said upper run, a hollow former adjacent said delivery end, means actuated by the articles delivered from the conveyor to the receiving plate

when the plate has received a measured quantity of the articles to move the plunger and plate laterally of the conveyor and toward the hollow former, the receiving plate providing a support for the measured quantity of articles in the hollow former, means for clamping the measured quantity in the hollow former, means for withdrawing the plunger and plate from the former when the articles have been clamped therein, and means for preventing forward movement of the articles on the conveyor when the plunger and plate are moving to and from the hollow former.

3. In a machine of the class described, the combination of an endless conveyor, means for driving the conveyor continuously, rails adjacent the edges of the top run of the conveyor and normally below the same, means for supplying stacked articles to the receiving end of said upper run and delivering them at the other end, said articles extending beyond the conveyor and over the rails, means for raising said rails thereby to lift said articles above said conveyor, a plunger having a receiving plate in the path of the conveyor adjacent its delivery end adapted to receive

articles from the conveyor, means for moving said plunger and receiving plate across the path of the conveyor, and means actuated by forward movement of the articles on the conveyor when a definite quantity of articles have been received on said receiving plate to actuate said rail raising means whereby said articles come to rest and said plunger moving means is operated to move said plate and the articles thereon out of the path of the articles on the conveyor.

4. In a machine of the class described, the combination of a continuously driven endless conveyor carrying a continuous row of articles stacked on edge, a hollow former adjacent the conveyor, means whereby the continuously driven conveyor advances the articles intermittently, and means for measuring off and delivering a definite quantity of the articles from the leading end of the continuous row on the conveyor into the hollow former during the interval when the articles are at rest.
